TABULATING MECHANISM

Harry L. Lambert, Enfield, N. Y., assignor to Allen
Wales Adding Machine Corporation, Ithaca,
N. Y.

Application October 29, 1941, Serial No. 416,970

12 Claims. (Cl. 197—63)

This invention relates to printing machines of the kind in which a selectively controlled printing mechanism prints upon a record sheet confined against a platen at any of successive selective positions caused by relative movement between the platen and printing mechanism. Examples of this type of machine are typewriting and calculating machines with cross tabulating carriages. In machines of this cross tabulating carriage type, the carriage is urged in one direction relatively to the base and stopped successively in different selected positions by the tabulating stops that are adjustable to different positions to vary the particular locations in which the carriage is stopped. These stops are usually at the back of the machine and out of view of the operator while at the front of the machine, so that it has been inconvenient to set such tabulator stops in prior devices. In prior devices it has usually been necessary for the operator to go around to the back of the machine to set the tabulator stops properly, and when the operator is at the rear of the machine for this purpose it is not easy to observe the positions of the columns or zones of the record sheet relatively to the printing means, where one desires to stop the carriage.

An object of this invention is to provide an improved machine of this type in which relative movement of the carriage is stopped in succession at different printing positions by tabulating mechanism, with which the operator may easily and quickly adjust and set the tabulating stops in the desired stop positions while remaining in front of the machine, with which the tabulating stops may be set easily and accurately, even though the operator is not able to see them while adjusting them, with which the tabulating mechanism may be combined with one or more kinds of line spacing mechanism, and which machine is easily incorporated in existing types of machines and is simple, compact, practical, trouble-free and inexpensive.

Other objects and advantages will be apparent from the following description of one embodiment of the invention, and the novel features will be pointed out hereinafter in connection with the appended claims.

In the accompanying drawings:

Fig. 1 is a rear elevation of a cross tabulating carriage of a calculating machine in which the preferred embodiment of the invention is incorporated.

Fig. 2 is a fragmentary perspective view of a portion of the machine as seen from the rear.

Fig. 3 is a fragmentary rear view, on an en-

larged scale, of one of the tabulator stops of the machine and certain associated parts, shown in normal positions.

Fig. 4 is a fragmentary horizontal section of the same parts taken approximately on line 4—4 of Fig. 11.

Fig. 5 is an elevation of the carriage shown in Fig. 1 as viewed from the right hand end of that figure.

Fig. 6 is a transverse sectional elevation taken approximately on line 6—6 of Fig. 1.

Fig. 7 is a fragmentary cross section taken approximately on the line 7—7 of Fig. 1.

Fig. 8 is a fragmentary end elevation showing some of the parts of Fig. 5 in different positions.

Fig. 9 is a fragmentary rear elevation of some of the parts shown in Fig. 1 but disposed in different positions.

Fig. 10 is a cross section of a part of the carriage on an enlarged scale, taken approximately on line 10—10 of Fig. 1.

Fig. 11 is a similar view, on a still larger scale, illustrating the means for uncoupling a tabulating stop from its guide or supporting bar.

Fig. 12 is a view on the same scale and on the same plane as that of Fig. 11 but with the parts in the position illustrated in Fig. 10.

Fig. 13 is a fragmentary vertical section of a tabulator stop and associated parts, taken on the line 13—13 Fig. 11.

Fig. 14 is a fragmentary vertical section showing the tabulator stop engaging finger moved to a position in which it clears the tabulator stops.

Fig. 15 is a similar view illustrating mechanism for moving the tabulator engaging finger out of its stop engaging position automatically.

This invention is illustrated as incorporated in an adding or calculating machine of the cross tabulating carriage type, examples of which are shown in United States patents to Peters No. 1,386,021, of August 2, 1941, and White No. 1,571,567, of February 2, 1926.

In this illustrated embodiment of the invention, the cross tabulating carriage includes a frame 1, Figs. 1 and 2, rotatably mounting the usual platen 2. The frame of the machine mounts a guide member or tabulator bar 3, Figs. 5 and 6, which slidably supports a relatively traveling carriage bar 4 by suitable ball bearings 5 and 6. The carriage bar 4 mounts the frame of the carriage for sliding movement from side to side of the machine in a well known manner, and the paper record sheet is either applied to the platen 2 in front of a guide plate 7, Fig. 6, and guided around beneath the platen, or paper from

a roll 10 mounted on a spindle 11 supported from plates 12 of the frame, is guided over the upper edge of the plate 1 and downwardly around the platen, depending upon the use to which the machine is to be put. The paper is confined to the platen by suitable spring pressed fingers 8 with rollers 9 as usual in typewriters and calculating machines. The carriage is also provided with a rod 13 which extends between and connects the end frame members of the carriage, and the frame member 3 is provided with an extension or member 14 which straddles the rod 13 and carries rollers 15 which roll along opposite sides of the rod 13, so as to provide a rolling support for the carriage at the rod 13 as well as by the ball bearings between the carriage bar 4 and the frame member 3.

The bar or member 3 at its rear edge is T-shaped, with the head of the T extending vertically to form a flange 16 which is formed along its upper edge with rack teeth 17. A plurality of tabulator stops 18 are slidably and individually mounted on the flange 16 so as to be shiftable along the flange 16 into different selected positions. Each stop 18 is generally C-shaped, Fig. 12, in transverse cross section, with the main or closed part of the C extending along the rear face of the flange 16 and the arms at the open side of the C extending above and below the upper and lower edges of the flange 16, and also engaging over the upper and lower edges of the flange to prevent removal of the stop from the flange 16.

The upper end or cross part of each stop 18 is provided with spaced slots 19 which extend in directions crosswise of the flange 16, and are of a size and spacing to receive therein the teeth 17 on the flange 16. For this purpose the slots 19 extend entirely through the upper cross part of the C, as shown in Fig. 13, and a leaf spring 20, by reaction between the flange 16 and the lower part of the stop 18, urges the latter downwardly in a manner to engage the teeth 17 within the slots 19 and thereby couple the stop to the flange 16 of the bar 3. The space between the upper and lower cross parts of the C is sufficient to enable the stop to be raised while remaining attached to flange 16 and disengage the slots 19 from the teeth 17, as shown in Fig. 13, and when the stop is so raised, it is free to slide along the flange 16 to any desired position.

A spacer member 21 extends between and connects plates 12 supporting the paper roll 10, and a plate 22 is disposed between plates 12 and provided at its ends with flanged ears 23 through which the spacer member 21 extends. The plate 22, adjacent its lower edge, is provided with bent ears or lugs 24 which fit against the faces of plates 12 for the paper roll, and are secured thereto in any suitable manner such as by screws, so that the plate 22 is rigidly coupled to the plates 12 of the carriage frame. An uncoupling member 25 is disposed flat against the rear face of the plate 22 and confined thereto by screws 26 which are threaded into the plate 22. The heads of the screws 26 confine the member 25 to the plate 22, and the shanks of the screws pass through vertically elongated slots 27 in the member 25, so that the latter, while confined to the plate 22, is mounted for vertical sliding movement thereon to an extent limited by the engagement of the ends of the slots 27 with the screws 26. The lower end of this member 25 is bent horizontally to form a flange 28 which extends

beneath the flange 16 on the tabulator bar, as shown particularly in Figs. 11 and 12.

When the member 25 is in its lowermost position, the flange 28 clears the lower ends of all the stops 18 which are mounted on the flange 16, but when the member 25 is shifted upwardly to the extent permitted by the slots 27, this flange 28 will engage the lower edge of any stop 18 with which it may be in alignment, and shift that stop 18 upwardly into the position shown in full lines in Fig. 11. This disengages the slots 19 from the teeth 17 without disengaging the depending arm of the stop at the open side of the C from the upper edge of the flange 16.

15 An operating lever 29, Figs. 1 and 2, is provided with a bearing boss 30 which is pivotally mounted by a stud 31 on the plate 22. One arm of this lever 29 is pivotally connected by a pin 32 to the uncoupling member 25 by a connection 20 sufficiently loose to enable rocking movement of the lever 29 while causing vertical rectilinear movement of the uncoupling member 25. The other arm of the lever 29 is offset rearwardly to clear the adjacent plate 12 of the carriage frame, 25 and then extends upwardly and terminates in an operating finger piece 33 well above the carriage, and at one side of the paper roll 10 so as to be readily accessible for manipulation and operation by an operator while at the front of the machine.

Rotatably mounted in the frame of the carriage is a shaft 34, Fig. 2, which carries, adjacent one end, an operating arm 35 terminating in a finger piece 36, and a stop finger 37 is fixed 35 on shaft 34 intermediate of its ends. A suitable spring 38, Fig. 2, is connected to the arm 35 for rocking the shaft 34 in a direction to dispose the stop finger 37 against the rear face of the carriage member 4, see Fig. 10. While in this 40 position, the stop finger 37, at its lower end, is in a position to engage against a vertical side edge of any stop 18 which it may meet when the carriage is shifted in one direction sidewise of the machine. The lower edge of the plate 22 is 45 provided with a depending lug 39, Figs. 1 and 2, which, at its free end, is bent horizontally to a position above the flange 16 and at a height such that it normally clears the upper edges of the stops 18 when the latter are coupled to the flange 50 16 of the tabulator bar as shown in Fig. 12, yet at such height as to be engaged by the stops 18 when the latter are shifted upwardly into the full line positions shown in Fig. 11 in which they are uncoupled from the flange 16.

55 The lug 39 may be considered as an abutment facing the stop finger 37, and the distance between the finger 37 and the adjacent edge of the lug 39 is only slightly greater than the length of a stop 18, so that when the stop finger 37 is engaged against one side or vertical edge of a stop 18 as the carriage is moved in tabulating direction, a vertical movement of that stop 18 into the uncoupled position shown in Fig. 11 will carry the upper end of that stop 18 into a position between the lug 39 and finger 37. When such a stop 18 is elevated in this manner and confined between the lug 39 and the tabulating stop finger 37, the carriage may be moved to shift that uncoupled stop 18 along the flange 16 of the tabulator bar into any desired position. It is understood, of course, that when any such stop 18 is elevated in this manner, it is concomitantly uncoupled from the tabulator bar, and its upper end shifted into the path of movement 70 75 of the lug 39 on the carriage.

The carriage is urged in a direction for relative rectilinear movement along the tabulator bar 2 by any suitable resilient or yielding means, and in the particular, illustrated example, a flexible strap 40, Fig. 1, is wound upon a spring drum 41 which is rotatably mounted on the stud 42 carried by an arm 43 of the carriage frame. The free end of the strap 40 is coupled to a suitable part of the machine frame, such as to the bracket 14 which mounts the guide rollers 15. Through the spring in the drum 41, the carriage is urged yieldingly toward the right in Fig. 1, which movement is limited by engagement of the tabulating stop finger 37 with the stops 18 in succession.

When the movement of the carriage under the action of the spring drum 41 is prevented by the engagement of the finger 37 with any stop 18, and one desires to cause a movement of the carriage into a successive printing position, it is merely necessary to press the finger 36 of arm 35, which rocks the finger 37 into a position to clear the engaged stop 18, whereupon the carriage begins to move under the urging of the strap 40. The operator immediately releases the finger 36, and the spring 38 rocks the finger 37 back into a position to engage the next stop 18 as soon as the finger 37 has cleared the rear face of the stop 18 from which it has just been disengaged. The carriage travels until the finger 37 engages the next stop 18 in succession on the bar 16, and this positions the carriage in another suitable printing position. Successive movements may be caused in the same manner.

Before starting a tabulating operation, the operator sets the stops 18 in succession in the desired positions where it is desired to stop the carriage, and this pre-setting of the stops may be accomplished in a simple manner. For this purpose, the operator shifts the carriage against the action of setting the stops in succession is continued movement, and then releases the carriage for movement until it engages the first stop 18. When this occurs, the operator grasps the operating end 33 of the lever 29 and rocks that lever in a direction to elevate the uncoupling member 25, which at that time is below the stop 18 then engaged by the finger 37. The operator at the same time, holds the carriage against movement.

When the lever 29 is rocked in this manner, the uncoupling member 25 is elevated and it in turn, engages the stop 18 against which the finger 37 then abuts, and raises it from the normal, coupled position shown in Figs. 3 and 12, into the uncoupled position shown in Fig. 11, thus disengaging that stop 18 from the teeth 17 of the flange 16. Then while holding lever 29 operated, the operator shifts the carriage in either direction into the position where he desires to stop the carriage for the first printing operation. When that position is reached the finger 33 of lever 29 is released, and the stop is then automatically caused to re-engage or re-couple itself to the flange 16 of the tabulator bar by the action of the leaf spring 20 of that stop. The operator then depresses the finger 36 to cause a tabulating operation by movement of the carriage until the next stop 18 is engaged, and then this re-setting operation for that stop is conducted in a manner similar to that just described, so as to set that second stop in the desired position to stop the carriage in the position desired for the second printing operation. This operation of setting the stops in succession is continued

until all the stops are set in the desired limiting positions.

In order that the carriage may be moved to start a new cycle of tabulating operations and tension the spring drum 41 without being obliged to shift the finger piece 36 and through it the finger 37 to clear the tabulator stops 18, the lower end of the vertical side face of the finger 37, at the side opposite that face which engages the stops 18 during a tabulating operation, is beveled as at 44 in a manner to cause the stops 18 to cam the finger 37 aside automatically when the carriage is moved to tension the spring drum 41, ready for a new tabulating operation. Thus the finger 37 will be automatically cammed aside in succession by the stops during this return movement of the carriage, while tensioning the spring drum, 41.

From the foregoing, it will be observed that the operator while in any position at the front of the machine for performing the printing operations, may set the stops 18 in selected tabulating positions, with accuracy, even though the operator cannot, while doing so, see the stops 18 that are being set.

The carriage is also provided with the usual universal bar or bail 45 which is rockably supported upon the rod 13 extending endwise of the carriage between the frame members thereof. This universal bar 45 is of approximately the same length as the carriage so that it may be engaged, in any of the carriage positions, and operated by a suitable cam 47, Figs. 5 and 6, as usual in this type of machine, and as explained in the Peters and White patents hereinabove identified. One end of the member 48, Fig. 1, of the universal bar 45 extends beyond the pivot rod 13 and at its upper end carries a pivot stud 49 which rockably supports a platen rotating pawl 50. This pawl 50 engages with ratchet teeth of a ratchet wheel 51 fixed on one end of the platen, and a spring 52 acts between a tail of the pawl 50 and the lever 48 to rock the nose of the pawl yieldingly into engagement with the teeth of the ratchet wheel. Thus each time that the universal bar 45 is rocked by the cam 47, it will, through the pawl 50, impart to the ratchet wheel 51 and through it the platen a selected increment of rotary movement.

The extent of this increment of movement may be varied in any suitable manner well known in the art, but in the particular illustrated example, the upper end of the lever 48 is notched in a step-like manner, which steps, by engagement with a nose 54, limit the extent of retraction of the lever 48 and the universal bar 45, and thus the extent of retraction of the pawl 50. Since the forward movement of the pawl is always to the same extent, the movement given the platen depends upon the starting position of the pawl. The nose 54 is provided as a flange on one arm of a lever 55 which is hinged at 58a in the carriage frame, and is provided with an operating finger or arm 58.

Also rockably mounted on the rod 13, Fig. 1, is a lever 57, one end of which is forked so as to straddle another rod 53 forming part of the universal bar 45. This lever 57 also extends upwardly, Fig. 15, and at its free upper end rockably supports a by-pass pawl 59 which is urged into its effective position by a spring 60, but which yields when the pawl 59 is rocked in one direction, as well known for this type of pawl.

Also fixed on the shaft 34, Fig. 2, but adjacent the right-hand end of the carriage, is an arm 61 which extends into proximity to the by-pass pawl

59 and at its free end is bent and carries a roller 62. Intermediate of its ends, it also carries a roller 63. When the shaft 34 is released and urged by spring 33 into its normal position shown in Figs. 1 and 10, in which the stop finger 37 is in the position shown in Fig. 10, the arm 61 will position the roller 63 within the path of the bypass pawl 59. Thus when the universal bar 45 is rocked by the cam 47, the arm 57 thereof will move the by-pass pawl 59 in a direction for the pawl 59 to engage the roller 63 as shown in Fig. 10, and cam the arm 61 upwardly sufficiently to disengage the tabulating stop finger 37 from a stop 18 with which the finger 37 is engaged, and then immediately pass the roller 63 as shown by the dash lines in Fig. 15. When the finger 37 was rocked in this manner and then released, it caused the disengagement of the stop member 13 from that finger sufficiently to start tabulating movement under the urging of spring drum 41 and the immediately following release of the roller 63 allowed the finger 37 to be swung back into a position to engage the next stop 18 and thereby limit that increment of movement of the carriage.

When the universal bar 45 is returned to its normal or retracted position as usual in this type of machine, the by-pass pawl 59 will idly pass the roller 63 without causing any rocking movement of the shaft 34, this passing position being shown in full lines in Fig. 15, and the final return position by the dot and dash line in the same figure.

Also mounted on one end of the carriage by a stud 64, Fig. 1, is a lever 65. A spring 66 connected between a suitable part of the carriage frame and one arm of lever 65 urges that lever into the full line position shown in Fig. 1 until a limit pin 67, Fig. 1, on the lever 65 engages against an end frame member of the carriage. This lever 65 is provided with a laterally extending lug 68 which extends loosely through the opening of an eye 69, Fig. 7, in a plate 70 secured to an end portion of the carriage. The lug 68 slides idly in the eye 69 when the lever 65 is rocked about the pivot stud 64. The lever 65 is also provided with a lug 71 having an oblique cam edge 72 on the free end thereof, which, when the lever 65 is rocked, engages the roller 62 on the end of arm 61 and rocks the arm 61 in a direction to disengage the tabulating stop finger 37 from a stop in a manner similar to that by which the finger 37 was disengaged when the arm 61 was rocked by the universal bar, except that when the lever 65 is operated in this manner, it rocks the arm 61 and should then be immediately released and allowed to return to its normal position. This immediately releases the arm 61 so that the finger 37 may be returned to a position to engage the next stop 18 in the sequence.

This lever 65 also carries a roller 73, Fig. 5, which, during the rocking of the lever 65, engages one arm of a lever 74 also rockably mounted on the stud 56a, and rocks the lever 74 counterclockwise in Fig. 5. Another arm of the lever 74 is connected by a pivot pin 75 to a driving pawl 76 which also engages and operates the ratchet wheel 51 of the platen to cause a line-spacing operation of the platen whenever the lever 65 is rocked. A suitable click pawl is also provided for the ratchet wheel 51 to prevent retrograde movement of the platen and also aid in preventing overrunning of the platen during the paper advancing increment of movement of the platen. Thus it will be observed that the carriage may be released for a tabulating operation either by manually operating the finger piece 36 on arm

35, or by an operation of the universal bar 45, or by an operation of the lever 65. The universal bar 45 and the lever 65, when operated, however, also cause line-spacing increments of rotation of the platen, whereas operation of the lever 35 causes a tabulating operation without a line-spacing increment of rotation of the platen.

Additional means are also shown at the left-hand end of the carriage in Fig. 1, for imparting increments of rotation to the platen independently of any tabulating movement of the carriage, but inasmuch as the details of such means form no part of the present invention, they will not be described or more fully illustrated.

It is believed that the operation of the tabulating mechanism will be clear from the foregoing description, but will be briefly summarized. When setting up a sheet in the carriage preparatory to printing operations, the carriage is shifted in a direction to tension the spring drum 41, to the full limit of its movement, and then released to enable it to move until finger 37 engages the first of the stops 18. The operator then rocks the lever 29 to uncouple the stop then engaged by the tabulating finger 37, which uncoupling operation automatically shifts that stop into the elevated position in which it is confined between the lug 39 on the carriage and the finger 37. The carriage is then shifted to place the first stop in the desired position for the first printing operation, and then the lever 29 is released. The released stop automatically re-couples itself to the flange 16 of the tabulating bar.

The finger piece 36 is next rocked to cause the first tabulating operation, and as soon as the carriage comes to rest against the next stop 18 in the sequence, the operator again rocks the lever 29 to uncouple that second stop from the tabulator bar, and the carriage is then shifted in either direction to position that second stop in the desired position for the second printing operation for the second tabulating position. The lever 29 is now again released. These setting operations are continued until all of the stops are set in the desired positions. After that, when a printing operation is to be started, the carriage is moved to starting position which tensions the spring drum 41, and as the carriage is released it is moved by the drum 41, until it is stopped by the engagement of the tabulator finger 37 with the first stop 18. The carriage is released for tabulating movement to the next or second position in any of three ways: (1) by manual operation of the lever 35, (2) by operation of the universal bar 45, and (3) by manual operation of the line-spacing lever 65.

The stops may be reset by the operator without going around to the rear of the machine, and this greatly simplifies and accelerates the setting of the stops.

It will be understood that various changes in the details and arrangements of parts, which have been herein described and illustrated in order to explain the invention, may be made by those skilled in the art within the principle and scope of the invention as expressed in the appended claims.

I claim:

1. In a printing machine of the type employing a cross tabulating carriage carrying a platen, which carriage is mounted to move horizontally from side to side, a bar disposed along and adjacent said carriage, means yieldingly urging said

carriage in one direction relatively to said bar, a plurality of stops mounted on and individually and releasably coupled to said bar and, when released, movable along said bar for locating said stops in selected positions on said bar, a stop finger on said carriage engageable against one side of each of said stops in succession to position the carriage in printing positions determined by the relative positions of the stops as the carriage is given increments of movement from stop to stop, means for rocking said stop finger into a position to clear a stop with which it may be engaged, means operable on said finger when said finger is released from said rocking means for returning it to a position in which it will engage the next stop along said bar as the carriage is moved by said urging means, an abutment on said carriage which is disposed adjacent the opposite side of any stop engaged by said stop finger and normally clearing said stops as the carriage moves from side to side, and means accessible to an operator at the front of the machine for uncoupling any stop from said bar and moving a portion thereof into the path of said abutment, whereby the carriage may be manually moved to position such uncoupled stop into any desired position to represent the position of a column on a sheet in printing position on said platen.

2. In a printing machine of the type employing a cross tabulating carriage carrying a platen which carriage is mounted to move horizontally from side to side, a bar disposed along and adjacent said carriage, means yieldingly urging said carriage in one direction relatively to said bar, a plurality of stops mounted on and individually and releasably coupled to said bar and, when released, movable along said bar for locating said stops in selected positions on said bar, said carriage having an abutment normally clearing said stops when said stops are coupled to said bar, but engageable with a portion of any stop that is uncoupled from said bar during movement of said carriage against said urging means, a stop finger on said carriage engageable against each of said stops in succession during movement of said carriage by said urging means, to limit the extent of movement of said carriage, means selectively operable for causing said finger to clear any stop during movement of said carriage by said urging means, means for urging said finger back into stop engaging position, and means accessible from the front of said machine for selectively uncoupling from said bar any stop engaged by said finger.

3. In a printing machine of the type employing a cross tabulating carriage mounting a platen, and which carriage moves horizontally from side to side, a bar disposed along and adjacent said carriage, means yieldingly urging said carriage and bar relative to each other in one direction, a plurality of stops mounted on said bar for movement therealong and individually and releasably coupled to said bar so as to be releasably located in selected positions along said bar, each stop having a portion displaceable laterally of said bar automatically when that stop is uncoupled from said bar, a stop finger on said carriage and engageable with said stops in succession to position the carriage in printing positions as determined by the location of said stops, means for shifting said finger into a position to clear a stop with which it may be engaged, means for urging said finger back into stop engaging position when re-

leased, an abutment on said carriage disposed to closely confine between it and said finger any stop engaged by said finger and uncoupled from said bar, and which abutment is positioned to clear all stops coupled to said bar, and means accessible to an operator while at the front of said machine, for uncoupling from said bar any stop engaged by said finger and thereby moving said displaceable portion into a position to be engaged by said abutment.

4. In a printing machine of the type employing a carriage mounting a platen and which carriage is mounted to move horizontally, a tabulating bar disposed along and adjacent said carriage, means yieldingly urging said carriage in one direction relatively to said bar, a plurality of stops mounted on and individually and releasably coupled to said bar, spaced means on said carriage for receiving between them any stop aligned with the space between them, one of said spaced means being yieldingly urged into a position to engage said stops in succession upon movement of said carriage, the other of said spaced means normally clearing said stops during movement of said carriage, means for shifting said one of said spaced means out of said stop engaging position, to clear said stops upon movement of said carriage, and means accessible from the front of the machine for uncoupling any stop engaged by said one of said spaced means and shifting a portion thereof into the path of said other of said spaced means.

5. In a printing machine of the type employing a carriage mounting a platen and which carriage is mounted to move horizontally, a tabulating bar disposed along and adjacent said carriage, means yieldingly urging said carriage in one direction relatively to said bar, a plurality of stops mounted on and individually and releasably coupled to said bar, spaced means on said carriage for receiving between them any stop aligned with the space between them, one of said spaced means being yieldingly urged into a position to engage said stops in succession upon movement of said carriage, the other of said spaced means normally clearing said stops during movement of said carriage, means for shifting said one of said spaced means out of stop engaging position, a stop engaging part mounted on said carriage and positioned adjacent a stop which is aligned at any time with the space between said spaced means, said part being movable into engagement with that stop for uncoupling that stop from said bar and moving a portion thereof into said space between said means, and means mounted on said carriage and operatively connected to said stop engaging part and having an operating part extending into position for convenient operation by an operator at the front of the machine for actuating said movable stop engaging part to shift said stop into and out of position between said spaced means.

6. In a printing machine of the type employing a carriage mounting a platen and which carriage is mounted to move horizontally, a tabulating bar disposed along and adjacent said carriage, means yieldingly urging said carriage in one direction relatively to said bar, a plurality of stops mounted on and individually and releasably coupled to said bar, spaced means on said carriage for receiving between them any stop aligned with the space between them, means for shifting one of said means out of stop engaging position, a stop engaging part mounted on said carriage adjacent a stop which is aligned with the space

between said spaced means, means for yieldingly holding said part out of engagement with said stop, a member disposed for access by an operator positioned at the front of said machine and which is operable to move said stop engaging part into engagement with said stop against the action of said second yielding means for uncoupling said stop from said bar and moving a portion of said stop between said spaced means, whereby said stop may be shifted by said carriage along and relatively to said bar, and upon release of said member by said operator, said stop engaging part will be disengaged from said stop by action of said second yielding means so that said stop may be coupled to said bar in the position to which it has been shifted.

7. In a machine of the kind in which a selectively controlled printing mechanism prints upon a record sheet confined against a platen, in any of successive positions of relative rectilinear movement of the platen and printing mechanism, the improvement which comprises a carriage part, a base part, said parts being relatively movable to give such rectilinear movement, means acting between said parts for yieldingly urging them relative to each other in one direction, one of said parts having a tabulating bar extending in the direction of said relative rectilinear movement of said parts, a plurality of tabulator stops mounted on said bar for independent movement therewith, and each separately and releasably coupled thereto, a tabulator finger carried by the other of said parts and engageable in succession with said stops to limit said relative movement by said urging means to selected extents depending upon the positions of said stops on said bar, means for shifting said finger laterally of the direction of said movement to clear any stop, means for urging said finger back into its position to engage a stop when released, an abutment on said other of said parts normally clearing said stops while said stops are coupled to said bar, but engageable with any stop that is engaged by said finger and is uncoupled from said bar to limit movement of that uncoupled stop away from said finger, whereby any uncoupled stop disposed between said finger and abutment may be shifted by such relative movement to a new position on said bar and released for limiting subsequently such relative movement, and means accessible to an operator while at the front of said machine for uncoupling from said bar any stop engaged by said finger and holding it uncoupled during any portion of said relative movement necessary to position said stop at a desired position, whereby when a stop is recoupled to said bar after being positioned it will be effective to stop such relative movement by said urging means when said finger again engages it.

8. In a machine of the kind in which a selectively controlled printing mechanism prints upon a record sheet confined against a platen, in any of successive positions of relative rectilinear movement of the platen and printing mechanism, the improvement which comprises a carriage part, a base part, said parts being relatively movable to give such rectilinear movement, means acting between said parts for yieldingly urging them relative to each other in one direction, one of said parts having a tabulating bar extending in the direction of said relative rectilinear movement of said parts, a plurality of tabulator stops mounted on said bar for independent movement therewith, and each separately and releasably coupled thereto, each stop having a part shiftable

in a direction laterally of said bar when coupled and uncoupled therefrom, a tabulator finger carried by the other of said parts and engageable in succession with said stops to limit said relative movement by said urging means to selected extents depending upon the positions of said stops on said bar, means for shifting said finger laterally of the direction of said movement to clear any stop, means for urging said finger back into its position to engage a stop when released, an abutment on said other of said parts normally clearing said stops while said stops are coupled to said bar, but engageable with said part of any stop which has been shifted laterally of the bar by the disengagement of that stop from said bar, whereby any uncoupled stop confined between said finger and said abutment may be shifted along said bar and recoupled to the bar at any desired position therewith, and means engageable with any stop engaged by said finger under the action of said first urging means, for uncoupling that stop and holding it uncoupled while that uncoupled stop is shifted into a new position.

9. In a machine of the kind in which a selectively controlled printing mechanism prints upon a record sheet confined against a platen, in any of successive positions of relative rectilinear movement of the platen and printing mechanism, the improvement which comprises a carriage part, a base part, said parts being relatively movable to give such rectilinear movement, means acting between said parts for yieldingly urging them relative to each other in one direction, one of said parts having a tabulating bar extending in the direction of said relative rectilinear movement of said parts, a plurality of tabulator stops mounted on said bar for independent movement therewith, and each separately and releasably coupled thereto, an abutment carried by the other of said parts and normally clearing said stops during such relative movement, a tabulator finger also carried by said other of said parts and engageable in succession with said stops to limit said relative movement by said urging means, means for shifting said finger in a direction laterally of the direction of said rectilinear movement to clear any stop engaged thereby, means for urging said finger back into its position to engage a stop, each stop having a portion thereof shiftable, when uncoupling it from said bar, in a direction laterally of the direction of such rectilinear movement into a position in which it is confined between said finger and abutment while that stop is engaged by said finger, and means also carried by said other of said parts normally clearing said stops but engageable with any stop engaged by said finger for uncoupling it from said bar and shifting said portion of that stop into position for engagement by said abutment and for holding said stop so uncoupled, whereby any of said stops engaged by said finger may be uncoupled from said bar, shifted along said bar while confined between said finger and said abutment, and recoupled to said bar at any desired position therewith.

10. In a printing machine of the type employing a cross tabulating carriage mounting a platen and which carriage is mounted to move horizontally, a bar disposed along and adjacent said carriage, means yieldingly urging said carriage in one direction relatively to said bar, a plurality of stops mounted on and individually and releasably coupled to said bar, a shaft on said carriage mounted for rocking movement thereon about an

axis generally parallel to the direction of movement of said carriage, a finger carried by said shaft and engageable against each of said stops in succession to position the carriage in successive printing positions determined by the relative positions of the stops, an abutment also carried by said carriage in slightly spaced relation to said finger for engagement with any of said stops engaged with said finger while uncoupled from said bar, but clearing said stops while the stops are coupled to said bar, means for rocking said shaft to disengage said finger from any stop engaged thereby, means yieldingly urging said shaft in a direction to return said finger to a position in which it will engage the next stop, and additional means also operable on said shaft to rock it in a direction to clear any stop engaged thereby and during the same operation, line spacing said platen.

11. In a printing machine of the type employing a cross tabulating carriage mounting a platen and which carriage is mounted to move horizontally, a bar disposed along and adjacent said carriage, means yieldingly urging said carriage in one direction relatively to said bar, a plurality of stops mounted on and individually and releasably coupled to said bar, a shaft on said carriage mounted for rocking movement thereon about an axis generally parallel to the direction of movement of said carriage, a finger carried by said shaft and engageable against each of said stops in succession to position the carriage in successive printing positions determined by the relative positions of the stops, an abutment also carried by said carriage in slightly spaced relation to said finger for engagement with any of said stops engaged with said finger while uncoupled from said bar, but clearing said stops while the stops are coupled to said bar, means for rocking said shaft to disengage said finger from any stop engaged thereby, means yieldingly urging said shaft in a direction to return said finger to a position in which it will engage the next stop, additional means also operable on said shaft to rock it in a direction to clear any

stop engaged thereby and during the same operation, line spacing said platen, and a universal bar also mounted on said carriage and having means associated therewith for rocking said shaft, independently of said other shaft operating means, in a direction to disengage said finger from any stop engaged thereby and for also line spacing said platen in the same operation that disengages said finger.

12. In a printing machine of the type employing a carriage, a tabulating bar disposed along and adjacent said carriage, means for yieldingly urging said carriage and bar relative to each other in one direction, a plurality of stops mounted on said bar for movement therealong, each stop having a part shiftable in a direction crosswise of said bar, between one position in which it is individually coupled to said bar and another position in which it is uncoupled from said bar, means yieldingly urging said part into said one position, a member carried by said carriage and engageable with one end of said part when in said another position to push that stop in a single direction along said bar with said carriage when the carriage is shifted in said single direction, and clearing said part when the latter is in said one position, a second member carried by said carriage and engageable with that stop to shift it with the carriage in a direction opposite to that caused by said first mentioned member and shiftable selectively to clear that stop, and means carried by said carriage, and shiftable therewith into alignment with said part on any of said stops, and having an element selectively operable, when aligned with said part of any stop to move said part into said one position and uncouple that stop from said bar and couple it to said carriage for movement with the latter to any new position where it may be released for recoupling to said bar, whereby one may shift the stops to selected positions on said bar while grasping and manually moving said carriage in either direction.

HARRY L. LAMBERT.
